UNITED STATES PATENT OFFICE.

ORVILLE M. KNOX, OF KNOXBORO, NEW YORK.

RAILWAY CROSSTIE.

1,413,917.

Specification of Letters Patent. Patented Apr. 25, 1922.

Application filed August 31, 1921. Serial No. 497,088.

To all whom it may concern:

Be it known that I, ORVILLE M. KNOX, a citizen of the United States, residing at 5 Knoxboro, in the county of Oneida and State of New York, have invented certain new and useful Improvements in Railway Crossties, of which the following is a specification.

This invention relates to metal railway 10 cross-ties, and has for its object to improve the type of ties shown and described in my earlier Patents Nos. 685,213, of October 22, 1901, and 1,274,897, of August 6, 1918.

Both of my former patents show generally 15 a flat rectangular top-plate having down-turned end-portions, which practically close the opposite ends of the ties, and are relied upon mainly for preventing endwise creeping of the ties, and a central depending 20 longitudinally arranged web. The later patent shows similar reinforcing strips, which are provided with depending V-shaped spurs, which co-operate in a limited way with the end-portions for anchoring the 25 ties.

The present invention has for its particular object to simplify the construction and thereby greatly lessen the labor and cost of manufacture, by eliminating the down-turned end-portions, which have been found to seriously interfere with the proper and effectual draining of the ties, and to provide a metal tie of the class, whose opposite ends are open and unobstructed. And a further 35 object is to provide a number of relatively broad depending rectangular and transversely arranged lugs or spurs, which are disposed at regular intervals along the opposite lateral edges of the tie, for more effectually anchoring the tie throughout its length 40 in the ballast or other support.

I attain these objects by the means set forth in the detailed description which follows, and as illustrated by the accompanying drawing, in which—

Figure 1 is a top-plan view of the complete tie. Fig. 2 is a side elevation of the same. Fig. 3 is a bottom plan view of the tie. Fig. 4 is an end elevation of the main body of the tie. Fig. 5 is a vertical cross-section taken on line 5—5 of Fig. 2. And Fig. 6 is a detached edge view of one of the lug-supporting strips.

In the drawing, 2 represents the normally

flat rectangular top-plate of the tie, which is 55 perforated at 2' for securing the rail-supporting parts (not shown), and 2^a represents a central longitudinally extending web or blade, which depends from the bottom side of the plate 2, and whose length is substantially the same as the said plate. 3—3' 60 represent similar metal reinforcing strips, which are mounted at the opposite lateral under edges of the plate 2, and which are rigidly held in place by rivets 3^a which pass 65 through corresponding perforations in the plate and strips. The strips 3—3' are preferably substantially the same length as the plate 2, and from the underside of each strip depend similar transversely registering lugs 70 or spurs 3^b, all of which may be of the same size, but are preferably formed rectangular, so as to present a large number of relatively broad surfaces to the ballast or under-filling (not shown), in which the tie is embedded, 75 for preventing the endwise creeping of the tie. The opposite ends of the tie are preferably open and free from any obstructions which might prevent the free and ready 80 draining of the ballast beneath the tie.

By providing a large number of the relatively broad square-formed lugs 3^b, as shown, greater and more efficient anchorage is afforded; and by disposing said lugs at frequent intervals along the underside of 85 the body 2, greatly increases the anchorage, which in the present case is distributed more evenly throughout the length of the body 2, and tends to hold the tie immovably embedded in the ballast or filling. 90

The size, shape and frequency of the anchor lugs 3^b are material features in the present case. By their provision, I am able to entirely eliminate the depending end-portions of my former patents, which not only 95 reduces the amount of material and the cost of manufacture, but the more important functions of said end-portions are entirely taken care of by the said lugs.

By omitting the depending end-portions 100 referred to and disposing the principal anchoring means intermediate the ends of the plate 2, farther removed from the usual adjacent sloping margins of the road-bed, effectually prevents the endwise creeping of 105 the tie and the consequent loosening and crumbling of the ballast and its relatively soft earthy support.

Having thus described my invention, what I claim is—

A railway cross-tie comprising, in its entirety, a T-sectioned body having a deep, 5 depending web, a pair of narrow reinforcing strips rigidly secured to the horizontal portion of the body on opposite sides of the web

and spaced therefrom, and a plurality of rectangular broad-faced spurs carried by the strips and depending therefrom to approximately one-half the depth of the web. 10

In testimony whereof I affix my signature.

ORVILLE M. KNOX.
